JOSEPH H. GAY AND WILLIAM D. QUIGLEY, OF NEWARK, NEW JERSEY.

ADJUSTING DEVICE FOR THE LOWER-KNIFE SUPPORTING JAW-BEAMS OF LEATHER-SPLITTING MACHINES.

NO. 903,560. Serial No. 406,053. Specification of Letters Patent. Patented Nov. 10, 1908.

Application filed December 11, 1907. Serial No. 406,053.

To all whom it may concern:

Be it known that we, JOSEPH H. GAY and WILLIAM D. QUIGLEY, citizens of the United States, residing at Newark, in the county of 5 Essex and State of New Jersey, have invented a certain new and useful Improvement in Adjusting Devices for the Lower-Knife-Supporting Jaw-Beams of Leather-Splitting Machines, of which the following 0 is a specification.

The invention relates to hide splitting machines, and has for its object the adjustment of the lower knife supporting jaw beam to compensate for the sagging of the 15 middle portion of said beam due to its own weight, or pressure of the hide above, or both. This enables the knife throughout its whole length to be supported in a true horizontal plane, and prevents untrue splitting 20 of the hide.

In the accompanying drawings—Figure 1 is a rear view of the transverse beam which forms the lower knife-supporting jaw, showing our adjusting device attached thereto. 25 Fig. 2 is a section on the line 2. 2. of Fig. 1, showing also the knife, gage roll, spring roll and elastic roll in section. Fig. 3 is a section on the line 3. 3. of Fig. 1, the upper jaw being removed.

30 Similar letters of reference indicate like parts.

A is the lower knife-supporting jaw beam of a leather splitting machine secured at its ends to the side frames B by bolts and nuts 35 C, in the usual way.

D is the upper jaw disposed on the lower jaw and provided with the usual adjusting screws; E is the knife, F the gage roll, G the spring roll and H the elastic or rubber roll 40 which supports the spring roll. The hide I after passing between the gage and spring roll meets the knife edge and is split.

All of the aforesaid parts are old and well known.

45 In using leather splitting machines embodying the above described construction, we have found that while the bolts and nuts C secure the jaw beam A at its ends to the frames B, with sufficient rigidity, they do 50 not hold it from becoming depressed by the pressure of the hide above especially when thick parts of the hide are passing through the machine, or from sagging due to its own weight. The result is that as this part of 55 the jaw drops below the level of the ends,

the knife above it is no longer supported and also drops, so that instead of standing truly horizontal everywhere it is downwardly curved. This is fatal to accurate splitting, to the production of a true surface 60 on the split and also reduces the possible number of splits obtainable from the hide. Our device obviates this difficulty, and enables us to produce splits of unusual thinness with true surfaces. On the lower side 65 of the jaw beam A is secured at its ends by bolts K, a girder having an upper flange L and web M, which flange is about equal in width to the bottom of the jaw beam.

The upper surface of the flange L is recessed between the bolts K, as shown at N. At the middle of the flange L are placed two adjusting screws O, P, which bear against the bottom member Q of the jaw beam A, or may be threaded to enter threaded apertures therein. Said screws are disposed one behind the other, so that one screw O acts on the front part of the member Q, and the other P, on the rear part. Between the screws O and P is a third screw R, which 75 passes downwardly through the bottom member Q, and enters flange L.

The girder web M is to be constructed of such dimension as to render said girder stiffer than the jaw beam A. Hence when 85 the adjusting screws O, P, R, are suitably turned the middle portion of the beam A may be raised back to proper level, and by adjusting the screw O or the screw P, said beam may also be slightly tilted in one direction or the other to correct any skewing 90 or like deviation from true horizontality.

We claim:

1. In combination with the lower knife jaw beam of a leather splitting machine, and with means for supporting and fastening said beam at its ends, means for adjusting the intermediate portion of said beam to compensate for the downward sagging thereof. 100

2. In combination with the lower knife jaw beam of a leather splitting machine, and with means for supporting and fastening said beam at its ends, means for tilting the intermediate portion of said beam. 105

3. In combination with the lower knife jaw beam of a leather splitting machine, and with means for supporting and fastening said beam at its ends, means for adjusting the intermediate portion of said beam to 110

compensate for the sagging thereof and means for tilting said portion.

4. In combination with the lower knife jaw beam of a leather splitting machine, and with means for supporting and fastening said beam at its ends, a girder having a flange secured at its ends to the lower face of the lower member of said beam, and adjusting screws in said flange disposed between said beam supports and acting on said lower face.

5. In combination with the lower knife jaw beam of a leather splitting machine, and with means for supporting and fastening said beam at its ends, a girder having a flange secured at its ends to the lower face of the lower member of said beam, and an adjusting screw disposed between said beam supports and in the lower member of said beam and acting on the said girder flange.

6. In combination with the lower knife jaw beam of a leather splitting machine, and with means for supporting and fastening said beam at its ends, a girder having a flange secured at its ends to the lower face of the lower member of said beam, adjusting screws in said flange and disposed between said beam supports and acting on said lower face, and an adjusting screw in said lower member and disposed between said first named screws and acting on said girder flange. 25

In testimony whereof we have affixed our signatures in presence of two witnesses.

JOSEPH H. GAY.
WILLIAM D. QUIGLEY.
